Primary Examiner — Freda S Nunn(74) *Attorney, Agent, or Firm* — Terrile, Cannatti, Chambers & Holland, LLP; Robert W. Holland(57) **CLAIM**

We claim the ornamental design for an information communication device housing, as shown and described.

DESCRIPTION

FIG. 1 is a front lower perspective view of the information communication device housing comprising the present invention;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front upper perspective view thereof installed to engage with other communication components mounted on a wall.

Broken lines shown in the drawings illustrate portions of the information communication device housing, and form no part of the claimed design.
